COUNTING, STACKING, AND PACKING
MACHINERalph K. Pottle, New York, N. Y., assignor to
American Can Company, New York, N. Y., a
corporation of New Jersey

Application October 30, 1946, Serial No. 706,682

12 Claims. (Cl. 226—14)

1

The present invention relates to a machine for counting, stacking and packing flat articles such as can ends and the like and has particular reference to a machine in which the received articles are arranged in stacks and the stacks are deposited into containers ready for shipment or storage.

An object of the invention is the provision of a counting, stacking and packing machine wherein flat articles to be packed are fed in a continuous procession without any interruption, a predetermined number of articles being counted out and formed into a stack and automatically inserted into a container ready for sealing.

Another object is the provision of such a machine wherein a predetermined number of articles are diverted for inspection purposes after the completion of every stack so that a visual check may be had on the articles being packed.

Another object is the provision of such a machine wherein the containers, into which the articles are being packed, may be sealed while in the machine to facilitate handling of the filled containers.

Numerous other objects and advantages of the invention will be apparent as it is better understood from the following description, which, taken in connection with the accompanying drawings, discloses a preferred embodiment thereof.

Referring to the drawings:

Figure 1 is a top plan view of a machine embodying the instant invention, with parts broken away;

Fig. 2 is a longitudinal section taken substantially along the line 2—2 in Fig. 1, with parts broken away;

Fig. 3 is a top plan section taken substantially along the broken line 3—3 in Fig. 2, with parts broken away;

Figs. 4 and 5 are transverse sections taken substantially along the broken lines 4—4, 5—5 in Fig. 2, with parts broken away;

Fig. 6 is an end elevation as viewed from the left in Figs. 1 and 2, with parts broken back and parts shown in section; and

Fig. 7 is a partial side elevation showing a clutch detail, with parts broken away and parts in section.

As a preferred embodiment of the instant invention the drawings illustrate a machine for counting out a predetermined number of sheet can ends A (Figs. 1 and 2) and for stacking them into a fibre tube or container B. In the instant machine 250 can ends are stacked into each tube. At the termination of each count of 250 can ends, two or more ends as the case may require, are set aside for inspection purposes.

When a tube B is filled with its stack of 250 ends, the top end of the tube is folded over manu-

ally and sealed in any suitable manner, as by the application of an adhesive tape or the like. Following the sealing of this end of the tube, the filled tube is turned over manually into an inverted position. While in this inverted position the open end of the tube is folded over and sealed manually in a manner similar to that employed for sealing the opposite end.

The operation of the machine is continuous, the counting, inspecting and stacking operations being effected without any interruption in the flow of can ends through the machine. The can ends A to be counted and stacked are received from any suitable source in a continuous procession. If desired these can ends may come direct from the presses which produce them.

The can ends as they are received in the machine fall into position on top of a stack of such ends located in a magazine 21 (Figs. 1, 2 and 6) which is bolted to a plate 22 mounted on the top of a frame 23 which constitutes the main frame of the machine. Guide bars 24 secured in the top of the magazine keep the ends in place in the stack.

The can ends in a magazine are disposed at an angle to the horizontal, the lowermost can end in the stack being supported at two oppositely disposed points adjacent its outer edge and transversely of the machine. The lowermost edge portion of this can end rests on a stationary step 26 formed in a guide rail 27 secured to the plate 22 and extending through the magazine 21. The opposite, upper edge portion of the can end rests on a ledge 28 of a rotatable cut-off knife or element 29 which is disposed in an opening 31 in the side of the magazine.

The cut off knife 29 is cylindrical in shape and is formed with a wide spiral thread 32 which extends out to and is an extension of the ledge 28. This arrangement provides a wedge shaped cut-off blade 30 which is mounted on the upper end of a drive shaft 34 journaled in bearings 35 formed in the plate 22 and in the frame 23. The shaft is rotated continuously in any suitable manner in time with the other moving parts of the machine. This is a conventional cut-off device used in many can making machines.

Rotation of the cut-off knife 29 separates the two lowermost can ends at the bottom of the stack in the magazine. This is effected by the rotating cut-off blade 30 at the upper end of the groove 32, cutting in between the second can end from the bottom and the can end next above. Hence for each rotation of the cut-off knife, one pair or two can ends as a unit are separated from the remaining can ends in the stack and are moved down through the spiral groove in the knife. The guide rail step 26 functions as a hinge point. At the lowermost end of the spiral groove 32, the pair of can ends drop free of the cut-off

knife and come to rest on the plate 22. They are then in an opposite inclined position with the one edge portion still supported on the step 26 of the guide rail 27. A shoulder 37 on the bottom of the cut-off knife temporarily retains the two ends in this position.

While in this downwardly inclined position, the pair of can ends are fed as a unit from the magazine 21 and are advanced along a short straight line path of travel toward the tube B in which they are to be stacked. This advancement of the can ends is effected by a spring held feed dog 41 (Figs. 1 and 2) which is disposed in a recess 42 formed in a reciprocating feed or stroke bar 43 (see also Fig. 6). The stroke bar extends longitudinally of the machine in a slot 45 formed in the plate 22 and operates in a slideway 46 formed in the machine frame 23.

The feed bar 43 is reciprocated through a forward or feeding stroke and thence through a return stroke in time with the separation of the can ends from the stack within the magazine, there being one feeding stroke for each pair of can ends. For this purpose the feed bar is formed with a pair of depending lugs 48 (Fig. 2) which carry a pivot pin 49 mounted in one end of a short link 51. The opposite end of the link is pivotally carried on the upper end of an actuating arm 52. This arm is mounted on a pivot pin 54 carried in a pair of spaced bearing blocks 55 (see also Fig. 3) which extend inwardly from the machine frame 23.

Intermediate its ends, the arm 52 is pivotally connected to the outer end of a crank link 56. The inner end of the link is mounted on a crank pin 57 secured in a crank disc 58 (see Figs. 2, 3 and 4) keyed to a rotatable crank shaft 59. The crank shaft is journaled in a long bearing 62 formed on the machine frame 23. This shaft is rotated continuously by a spur gear 63 which is mounted on the outer end of the shaft and which meshes with a gear 64 mounted on a main drive shaft 65. The main drive shaft extends transversely of the machine in parallelism with the crank shaft 59 and is journaled in bearings 66 formed in the frame.

This main drive shaft 65 is rotated in any suitable manner at a speed which gives it one rotation for every unit or pair of can ends separated by the cut-off knife 29 from the bottom of the stack of ends in the magazine 21. Thus the speed of the main shaft is timed with the separation of the ends. The gears 63, 64 are made of equal pitch diameter and thus the crank shaft rotates at the same speed as the drive shaft. This provides proper reciprocation of the feed bar 43 in time with the separation of the can ends.

On a forward or feeding stroke of the feed bar 43 its feed dog 41, engaging behind the pair of can ends A separated from the stack in the magazine 21, advances these two ends along the guide rail 27 and a cooperating parallel rail 71 which is disposed adjacent the cut-off knife 29. A clearance opening 72 formed in the side of the magazine adjacent its base permits of this feeding of the can ends from the magazine. The step 26 of the rail 27 is tapered downwardly along this path of travel so that the pair of can ends shift from an inclined position into a horizontal position as the ends advance along the rail.

At the end of the feeding stroke, the feed bar 43 delivers the pair of can ends into and between a pair of rotating stacker worms 75 (Figs. 1, 2 and 4) located at a can end stacking station C. The feed bar then moves back through a re-

turn stroke to its original position. At the time the bar begins this back stroke the next pair of can ends to be advanced has already been separated from the remainder of the stack in the magazine. Hence during the return stroke, the feed dog 41 engages this pair of ends and is depressed as the dog travels back under them.

The separated can ends are held against backward movement during this travel of the feed dog, by a pair of holding fingers 76 (Figs. 1 and 2) which are located one on each side of the separated can ends. These fingers are mounted on pivot pins 77 one of which is secured in the plate 22 and the other of which is fastened in the guide rail 27. A coil spring 78 around each pin normally holds the fingers in an inwardly projected position. A stop pin 79 adjacent a tail piece on each of the fingers 76 and secured in the plate 22 limits the inward travel of the fingers but permits outward movement for a purpose which will be hereinafter explained.

The stacker worms 75 are mounted in a vertical position on the upper ends of a pair of spaced and parallel worm shafts 86. These shafts extend down through the plate 22 and are journaled in bearings 87 formed in the machine frame 23. The shafts are continuously rotated in time with the other moving parts of the machine by helical gears 88 which are carried on the lower ends of the shafts. These helical gears mesh with and are driven by similar helical gears 89 (Figs. 3 and 4) mounted on the main drive shaft 65. The speed of the worm shafts is equal to one revolution for each unitary pair of can ends fed into the worms 75.

Pairs of can ends fed into the worms 75 are elevated by the worms between a plurality of vertical guide bars 92. There are four of these bars located two adjacent each stacker worm 75 and they are secured to curved brackets 93 bolted to the plate 22.

As the pairs of can ends A in the rotating stacker worms 75 move upwardly to a position adjacent the top of the worms they snap past a pair of spring held support fingers 95 (Figs. 1, 2 and 4) and build up into a stack D. The stack rests on the tops of the two stacker worms 75 and the two fingers 95 and is retained in position by the guide bars 92. The support fingers 95 are pivotally mounted on a U-shaped bracket 96 which surrounds one of the stacker worms. This bracket is formed on the inner end of a long arm 97 (see also Figs. 4 and 5). The outer end of the arm is mounted on a support shaft 98 carried in a pair of spaced bearing brackets 99 bolted to the top of the machine frame 23.

As the stack D of can ends builds up, by the addition of pairs of can ends to the bottom of the stack, the upper end of the stack moves up into a tube holder or head 111 (Fig. 2) of an intermittently rotatable turret 112. This turret is mounted on a vertical shaft 113 which is carried in a long vertical bearing 114 formed as a part of the machine frame 23 and is mounted for movement above the stacker worms 75.

The turret 112 is formed with a plurality of the heads 111 and one head at a time passes into alignment with the stacker worms 75 at the stacking station C for the reception of a stack D of can ends. Each head as it comes into the stacking station C carries a tube B open at both ends. The tube has been manually inserted into the head and it is into this tube that the can ends are stacked while the head is stationary at the stacking station. The tube in its head is in an

upright, slightly inclined position, as best shown in Fig. 2.

The lower open end of the tube B is held in a mouth or opening 121 (Figs. 2 and 5) of a retainer ring 122. The ring is secured in a recess 123 formed adjacent to and located above a cylindrical pocket 124 in the head 111. The retainer ring 122 is provided with an inverted funnel device 126 which extends up inside the tube B. This device guides the stack of can ends as it enters into the tube.

The funnel member 126 comprises a plurality of segmental tapered and hinged fingers 128 which are arranged within the mouth 121 of the retainer ring 122. The lower ends of these fingers are mounted on pivot pins 129 carried in the ring. Each finger, adjacent its pivot pin is formed with a lug 131 which is engaged by a coiled spring 132 which encircles all of the fingers. This spring normally holds the fingers inwardly to form the inverted funnel structure.

As the stack D of constantly rising can ends builds up into the tube the ends push the funnel fingers 128 outwardly against the resistance of their spring 132. This movement of the fingers clamps the tube in place and thus permits the can ends to enter the tube readily without dislodging the tube from its retainer ring. Clamping of the tube is brought about by projections which are formed on the fingers and which press the tube into matching indentations formed in the ring 122. The funnel fingers remain in this pushed back position as long as the ends are building up and while the tube is being filled.

The can ends moving up into the tube B are prevented from dropping back by a pair of retaining fingers 135 which are disposed directly below the funnel fingers 128. These retaining fingers are located in the head pocket 124 and are mounted on pivot pins 136 secured in the head 111. Spring barrels 137 carried in the head, press against the fingers and force them inwardly into the path of travel of the can ends moving up into the tube. The can ends snap past these fingers as they pass into the head. Tail lugs 138 formed on the fingers engage and limit the inward travel of the fingers.

In the instant machine, each tube B is adapted to receive 250 separate can ends. This is 125 pairs of can ends as fed from the magazine 21 by the feed bar 43. Thus the feeding of sufficient can ends to fill one tube B requires 125 feeding strokes of the feed bar 43.

The counting of these required can ends and strokes of the feed bar 43 is effected by a simple gear counting mechanism which includes a properly proportioned continuously operating gear train and a clutch device. For this purpose the driving gear 63 (Figs. 3 and 4) of the feed bar crank shaft 59 is formed integrally with a counter pinion 142 which meshes with and drives an intermediate idler gear 143. The idler gear is mounted on a short idler shaft 144 journaled in a bearing 145 formed in the machine frame 23. The idler shaft is continuously rotated.

The idler shaft 144 carries a driving pinion 147 which meshes with and drives a cam shaft gear 148. This gear is loosely mounted on one end of a normally stationary cam shaft 149 (see also Figs. 2 and 5) which carries a one revolution clutch 150. The cam shaft is carried in bearings 151 formed in the machine frame 23. The gear 148 rotates continuously at a speed 21 times slower than the feed bar crank shaft 59. In other words the cam shaft gear makes one revo-

lution for every 21 revolutions of the crank shaft and for the feeding of 21 sets or pairs of can ends.

The cam shaft gear 148 is formed integrally with a driving pinion 155 (Figs. 3 and 5) which meshes with and drives a clutch gear 156. This clutch gear is mounted on a short shaft 157 which is journaled in a long bearing 158 formed in the machine frame 23. The gear 156 completes the counting gear train and is continuously rotated at a speed of one revolution for every 125 pairs of can ends fed by the feed bar 43.

Hence during one complete cycle of operation of the machine the reciprocating feed bar 43 continuously feeds 125 pairs of can ends A into the stacker worms 75 for stacking into a tube B while the counting gear train operates to rotate the clutch gear 156 through one complete revolution. As the feed bar 43 moves forward through its 125th feeding stroke and thus advances the 125th pair of can ends into position in the stacker worms 75, the clutch gear 156 completes its single revolution. Thereupon the clutch 150 is operated and this sets the cam shaft 149 in motion for one complete revolution.

Operation of the clutch 150 is effected by a cam 161 (Figs. 3, 5 and 7) which is formed on the side of the clutch gear 156. The cam actuates a cam roller 162 which is carried on the upper end of a lever 163. The lower end of the lever is mounted on a rocker shaft 164 carried in a pair of spaced bearings 165 which depend from the machine frame 23. Between the bearings the rocker shaft 164 carries a flapper plate 167 of the clutch 150.

The flapper plate 167 normally is in a position to engage against a clutch dog 171 (Fig. 7). The dog is pivotally mounted in a recess 172 formed in a clutch barrel 173 of the clutch 150. The clutch barrel is secured to the cam shaft 149. The dog within its recess 172 is backed up by a spring barrel 175 located in a bore in the clutch barrel 173.

As the clutch gear 156 approaches the end of its single revolution, its cam 161 rocks the lever 163 and the flapper plate 167 inwardly. This movement of the flapper plate releases the clutch dog 171 from its flapper plate engaging position and hence its spring barrel 175 forces the dog outwardly. The clutch dog thus engages the inner surface of a clutch ring 177 which surrounds the clutch barrel and which is formed on the continuously rotating cam shaft gear 148. The outer end of the released clutch dog immediately falls into a notch 178 (Fig. 7) formed in the rotating clutch ring 177. This locks the gear 148 and the cam shaft 149 together for one complete rotation of the cam shaft.

During this one revolution of the cam shaft the flapper plate 167 is returned to its normal position so as to reengage the clutch dog 171 at the end of the rotation. Engagement of the dog releases it from the clutch ring notch 178 and the cam shaft thereupon stops while the gear 148 continues to rotate through a new cycle.

The single rotation of the cam shaft 149 effects a plurality of operations which take place in proper sequence through cams mounted on the shaft and which will now be explained. The first of these operations is the discharge from the magazine 21 of two can ends for inspection purposes. This is brought about by a discharge dog 181 (Figs. 1, 2 and 6) which is pivotally mounted in a recess 182 formed in the feed bar 43 adjacent and to the rear of the feed dog 41. This dog is normally depressed below the upper surface of the

feed bar and hence is inactive during the filling of the tube B as already described.

Intermediate its ends, the discharge dog 181 is formed with a depending arm 183 (Figs. 2 and 6) which carries a roller 184. The roller 184 of the discharge dog is disposed adjacent a longitudinal track 186 which extends along and below the path of travel of the feed bar 43. This track is formed on the outer end of a lever 187 (see also Fig. 3) which is mounted on a pivot shaft 188 carried in a pair of spaced bearings 189 formed on the machine frame 23. This lever is formed with an inner arm 191 which carries a cam roller 192. The cam roller operates against an edge cam 193 mounted on the cam shaft 149. A spring 194 stretched from the arm 191 to a pin 195 in a lug 196 of the bearing 145, keeps the cam roller in engagement with the cam.

During normal operation of the feed bar 43 the roller 184 of the discharge dog 181 is out of engagement with the track 186 and this keeps the dog depressed so that it readily passes under the can ends in the magazine 21. However, just as soon as the feed bar 43 begins the return stroke following its 125th feeding stroke, which is coincident with the beginning of rotation of the cam shaft 149, the cam roller 192 on the arm 191 falls into a notch 198 (Fig. 2) in the cam 193 and this rocks the lever 187 upwardly. This upward movement of the lever lifts the track 186. The track engages and raises the dog roller 184 and thus lifts the discharge dog 181 above the top surface of the feed bar.

With the discharge dog 181 in an elevated position during the 125th return stroke of the feed bar, the dog engages and discharges from the magazine 21 the 126th pair of can ends A. The dog pushes this pair of ends backward, past the holding fingers 76 (Figs. 1 and 2) through an opening 199 in the side of the magazine and delivers these ends into a chute 201 secured to the machine frame 23. The chute directs these two can ends to any suitable place of deposit for inspection purposes.

As soon as the discharge dog 181 has delivered the 126th pair of can ends into the chute 201 for inspection, the cam roller 192 of the arm 191 rides out of the cam notch 198. This rocks the lever 187 back into its original position and thus permits the discharge dog 181 to fall back into its depressed position in the feed bar.

Since the 126th pair of can ends has been diverted for inspection purposes on the 125th back stroke of the feed bar 43 there are no separated can ends ready in the magazine to be fed forward on the next following or 126th feeding stroke of the feed bar. Hence on this stroke of the feed bar no can ends are fed forward. This creates a space or skip in the continuous feeding operation of the feed bar and thus marks the termination of one feeding cycle of 125 pairs of can ends.

During this diversion of can ends for inspection purposes the 125th pair of can ends has reached the top of the stacker worms and has snapped past the support fingers 95. Since the 126th pair of ends was diverted from the stacker worms, the thread of each worm immediately below the 125th pair of ends is empty and thus a space is created between the completed stock and the beginning of a new stack. While this space is existent the entire stack D is lifted vertically into a position where it is supported on the retaining fingers 135 in the turret head 111. This lifting of the stack is timed to start as soon as the 125th pair of ends reaches the top of the

worms and is carried out in a relatively slow lift since plenty of space has been provided between the top of the worm and the bottom of the turret to permit the completion of the lifting operation before the new stack builds up to the bottom of the turret.

The lifting of the stack D of can ends into the head 111 is effected by an upward movement of the support fingers 95 and the U-shaped bracket 96 in which they are carried. For this purpose the bracket support shaft 98 carries a depending lever 205 (Figs. 2, 3 and 5) having mounted on its lower end a cam roller 206. This roller operates on an edge cam 207 secured to the cam shaft 149. A tension spring 208 keeps the roller in engagement with the cam. One end of the spring is hooked into the lever while the opposite end is secured in a lug 209 formed on the machine frame 23. It is the rotation of the cam 207 with the cam shaft 149 that rocks the bracket shaft 98 and thus raises and lowers the bracket 96 and the support fingers 95, as hereinbefore mentioned.

With the entire stack of 250 can ends resting on the retaining fingers 135 of the head 111, the turret 112 is rotated through a partial rotation on its shaft 113. This rotation of the turret removes the head 111 and its partially filled tube B, from the stacking station C into an idle station and also brings the next following head with an empty tube B into place to receive the next stack of ends as it builds up, as just explained.

This rotation of the turret 112 is brought about by an indexing plate 211 (Figs. 2 and 5) carried on the lower end of the turret shaft 113 and an indexing cam 212 (see also Fig. 3) mounted on the cam shaft 149. The indexing plate 211 carries a plurality of cam rollers 213, one for each head 111, arranged in a circle adjacent the outer periphery of the plate. These cam rollers are individually engageable by and operate in an interrupted cam groove 214 formed in the cam 212. This is a conventional indexing mechanism.

During the single rotation of the cam shaft 149 one of the cam rollers is engaged by the groove 214 of the indexing cam 212 and is shifted longitudinally of the cam. This movement of the cam roller partially rotates the indexing plate 211 and the turret shaft 113 and the turret 112 secured thereto.

The partial rotation of the turret 112 also shifts a previously partially filled tube B and its head 111 into a pusher or inserting station E (Figs. 1, 4 and 5). At this station the stack of can ends A resting on the retaining fingers 135 in the head 111 is pushed up into the place it is to occupy in the tube B, above the funnel fingers 128. As the lowermost can end in the stack passes up above the funnel fingers, these fingers close in beneath the stack and hold it in proper position within the tube, as best shown in Fig. 2. These fingers also locate the lower end of the stack in spaced relation to the lower end of the tube so that sufficient material of the tube is available at the ends for sealing purposes. In this respect the fingers serve a dual purpose.

This pushing up of the can ends into the tube is effected by a normally stationary plunger or lifter element 216 (Figs. 4 and 5) which is disposed below the path of travel of the heads 111 of the turret 112. This plunger is secured to the upper end of a nearly vertical movable plunger rod 217 slidably disposed in a long upright bearing 218 formed on the machine frame 23.

The lower end of the rod is connected by a

short link 219 to the outer end of a bell crank 221 mounted on a pivot pin 222 carried in a bearing 223 (see also Fig. 3) secured to the machine frame. The opposite end of the bell crank carries a cam roller 225 which operates in a cam groove 226 of a barrel cam 227 mounted on the cam shaft 149.

The rotation of this cam with the single rotation of the cam shaft 149 forces the plunger up into and through the head 111 while the turret is stationary and thus lifts the stack of can ends into their proper place within the tube B. After such a pushing or inserting operation the plunger immediately returns to its original position in readiness for the next head 111 and its partially filled tube B.

This pushing or inserting operation completes the cycle of operations performed by the single rotation of the cam shaft 149 and also completes the mechanical operations of counting a predetermined number of can ends and stacking them into a tube B. The cam shaft 149 upon the completion of this cycle ceases rotation, through withdrawal of the clutch dog 171 and remains stationary through the following feeding operations of the feed bar 43.

While the turret 112 remains stationary during the stacking of subsequent can ends into another stack at the stacking station C, the upper end of the filled tube B at the pusher station E, is folded over in any suitable manner and may be sealed as by the application of adhesive tape or the like. This sealing of the filled tube is a manual operation and is performed preferably by an operator located at this station.

Upon subsequent partial rotation of the turret 112, the filled and partially sealed tube B is carried around through an idle station and thence into a discharge station F (Figs. 1 and 2). At this station an operator tilts the filled tube outwardly into inverted position and deposits it in a stationary holder 231. Holder 231 is secured by a bracket 232 to the machine frame 23. This action removes the tube from its head 111 of the turret 112. While in this inverted position in the holder 231, the operator manually folds the open end of the tube down into place against the can ends and seals it as by the application of an adhesive tape or the like.

With the filled tube sealed at both ends, the tube is discharged manually to any suitable place of deposit for shipment or storage. This completes the operations performed in the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for counting, stacking and packing flat articles, the combination of stacking means including a stacking bracket for receiving a predetermined number of articles and for arranging them in stack formation within said bracket, support means movable into position adjacent said stacking means for holding a container to be filled with said articles, means for moving said bracket toward said support means to transfer the stack of articles into the support means, and inserting means for pushing said stacked articles into said container.

2. In a machine for counting, stacking and packing flat articles, the combination of stacking means for receiving a predetermined number of articles and for arranging them in stack formation, an intermittently rotatable turret disposed adjacent said stacking means, a plurality of heads carried on said turret for holding containers to be filled with said articles, means for moving said turret to position one of said heads with its held container into alignment with said stacking means, and inserting means operable after the said article stack formation has been completed for bodily pushing the stack of said articles into said aligned container.
3. In a machine for counting, stacking and packing flat articles, the combination of stacking means for receiving a predetermined number of articles and for arranging them in stack formation, an intermittently rotatable turret disposed adjacent said stacking means, a plurality of heads carried on said turret for holding containers to be filled with said articles, said heads and the containers held therein being movable into a plurality of working stations in the machine, means at one of said stations for receiving a stack of articles from said stacking means and for moving the stack into the adjacent turret head and partially within the container therein, and means at another of said stations for pushing the received stack of ends out of said head and into a predetermined position wholly within said container.
4. In a machine for counting, stacking and packing flat articles, the combination of stacking means for receiving a predetermined number of articles and for arranging them in stack formation, an intermittently rotatable turret disposed adjacent said stacking means, a plurality of heads carried on said turret for holding containers to be filled with said articles, said heads and the containers held therein being movable into a plurality of working stations in the machine, means at one of said stations for receiving a stack of articles from said stacking means and for moving the stack into the adjacent turret head and partially within the container therein, retaining fingers in said heads for holding the received stack of articles against displacement during rotation of said turret, and means at another of said stations for pushing the received stack of ends out of said head and into a predetermined position wholly within said container preparatory to sealing the container.
5. In a machine for counting, stacking and packing flat articles, the combination of stacking means for receiving a predetermined number of articles and for arranging them in stack formation, an intermittently rotatable turret disposed adjacent said stacking means, a plurality of heads carried on said turret for holding containers to be filled with said articles, said heads and the containers held therein being movable into a plurality of working stations in the machine, means at one of said stations for receiving a stack of articles from said stacking means and for moving the stack into the adjacent turret head and partially within the container therein, means at another of said stations for pushing the received stack of ends out of said head and into a predetermined position wholly within said container, and means within said heads and extending into the containers therein for locating and holding the fully inserted stack of articles in a container.
6. In a machine for counting, stacking and packing flat articles, the combination of stacking

means for receiving a predetermined number of articles and for arranging them as a unit in stack formation, an intermittently rotatable turret disposed adjacent said stacking means, a plurality of heads carried on said turret for holding containers to be filled with said articles, one of said containers being aligned with said stacking means, inserting means for moving the unit stack of said articles into said aligned container preparatory to sealing the containers, and means for holding said turret on its rest period during the insertion of the stacks of articles into said containers thereby properly positioning said heads and the containers relative to said stacking means.

7. In a machine for counting, stacking and packing flat articles, the combination of a pair of vertically disposed rotatable stacking worms for receiving articles and for elevating them into a vertical stack, support fingers disposed adjacent said stacking worms for receiving the articles from said worms and for supporting the stack as it builds up, a horizontal turret disposed above said worms, a plurality of heads carried on said turret for supporting tubular containers to be filled with said articles each turret head being alignable with said worms for receiving its stack of articles, means for moving said support fingers vertically to lift a predetermined number of articles built up in the stack on said fingers, retaining fingers in said head for holding the received stack of articles in place, means for partially rotating said turret for aligning the filled head at another station, vertically movable plunger means at the latter station for raising the stack into a predetermined position within said container, and a plurality of yieldable fingers carried in said head and forming an inverted funnel extending into the container for supporting said stack in its predetermined position within the container preparatory to sealing the container.

8. In a machine for counting, stacking and packing flat articles, the combination of a source of supply of articles to be packed, feeding means for advancing from said source a predetermined number of said articles along a path of travel, stacking means for receiving the advanced articles and for arranging them in stack formation, support fingers disposed adjacent said stacking means for holding said articles as the predetermined number builds up in the stack, a horizontally disposed turret above said stacking means, means carried by said turret for holding a container to be filled with said articles, and inserting means for pushing the stack of articles from said support fingers into said container.

9. In a machine for counting, stacking and packing flat articles, the combination of a pair of rotatable stacking worms for moving articles in processional order, support fingers disposed adjacent said stacking worms for receiving the articles from said worms and for supporting the same as they build up into a stack, an intermittently movable turret disposed at the delivery end of said worms, a plurality of heads carried on said turret for supporting tubular containers to be filled with said articles said turret heads being alignable successively with said worms, means for moving said support fingers after a predetermined number of articles have been stacked to partially insert the stack into an aligned and held container, and means spaced from said support fingers for moving the partially inserted stack fully into said container.

10. In a machine for counting, stacking and

packing flat articles, the combination of a pair of vertically disposed rotatable stacking worms for receiving articles and for elevating them into a vertical stack, a horizontal turret disposed above said worms, a plurality of heads carried on said turret for supporting tubular containers to be filled with said articles each turret head being alignable with said worms, support fingers disposed adjacent said stacking worms for receiving the articles from said worms and for supporting the same as they build up into a stack, means for moving said support fingers vertically to partially insert the stack into an aligned and held container, and means spaced from said support fingers for moving the partially inserted stack fully into said container.

11. In a machine for counting, stacking and packing flat articles, the combination of a pair of vertically disposed rotatable stacking worms for receiving articles and for elevating them into a vertical stack, a horizontal turret disposed above said worms, a plurality of heads carried on said turret for supporting tubular containers to be filled with said articles each turret head being alignable with said worms, retaining fingers carried in each head, support fingers mounted above said stacking worms for receiving the articles from said worms and for supporting the same as they build up into a stack, means for moving said support fingers vertically to transfer said stack of articles from said support fingers to said retaining fingers and to partially insert the stack into an aligned and held container, and means spaced from said support fingers for lifting said stack of articles from said retaining fingers to position the partially inserted stack fully into said container.

12. In a machine for counting, stacking and packing flat articles, the combination of a turret, a plurality of heads carried on said turret for supporting tubular containers to be filled with articles, means for intermittently rotating said turret to position said heads successively through a plurality of working stations including a stacking station, an inserting station, a sealing station and a discharge station, means at said stacking station for stacking a predetermined number of said articles as a unit stack, means also located at said stacking station for transferring the unit stack of articles into said turret, means at said inserting station for inserting the stack of articles carried by said turret into predetermined position within the corresponding container carried in said head, means at said sealing station for holding each filled container with its open end in position for sealing, and means at said discharge station for receiving and for directing the filled and sealed containers to a place of deposit.

RALPH K. POTTLE.
